UNITED STATES PATENT OFFICE

DONALD F. WHITING, OF PORT WASHINGTON, NEW YORK, ASSIGNOR TO WESTERN ELECTRIC COMPANY, INCORPORATED, OF NEW YORK, N. Y., A CORPORATION OF NEW YORK

ELECTRON TUBE CIRCUITS

Application filed November 21, 1924, Serial No. 751,202. Renewed January 22, 1931.

This invention relates to space discharge devices and particularly to circuits for energizing or controlling such tubes.

One object of this invention is to prevent fluctuations in the space current supply of a space discharge amplifier from producing disturbances in the output of the amplifier.

A further object of this invention is to prevent fluctuations in space current supply from being impressed on the grid through the use of a resistance in the plate circuit for obtaining a grid biasing potential.

It is often desirable to energize electron tubes from alternating current sources such as house lighting circuits. In such cases it is necessary to rectify the alternating current so as to obtain a direct current for the anode-cathode voltage. The output of the rectifier can be smoothed out to a considerable extent by the use of a simple inductance condenser filter. When smoothed out in this manner the supply voltage is usually sufficiently free of fluctuations that it can be used in the last stages of an amplifier without producing undesirable disturbances in the output. However, the power level in the first stages is so low particularly when very weak currents are being amplified, that small fluctuations, which may be present in the output of the usual smoothing out filter, may produce disturbances in the output of the first stages which are of the same order of magnitude as the amplified current.

In the types of vacuum tube apparatus which it is desirable to supply with rectified current, it is also usually desirable to eliminate all batteries, and the grid biasing potential must then be obtained in some manner such as by the use of a resistance in the space current circuit, the grid being connected to the terminal of the resistance adjacent to the negative terminal of the space current source in a manner well known in the art. By this arrangement, a potential proportional to the RI drop in the resistance, is impressed on the grid. If there are any fluctuations in the space current supply, the potential impressed on the grid will fluctuate in the same manner and the fluctuations will be amplified by

the action of the tube producing disturbances in the output.

It is a particular object of this invention to eliminate fluctuations in the plate and grid potentials supplied to the tubes in the first stages of an electron tube amplifier.

In general, the objects of this invention are accomplished by using resistance condenser filters. Since there is no direct current drawn by the grid of the tube, it is possible to include a high resistance in the circuit connecting the grid with the impedance used for obtaining the biasing potential. This high resistance will offer a considerable impedance to fluctuating currents and by using a condenser of moderate capacity connected in shunt to the circuit comprising this resistance and the grid biasing resistance in series, it has been found that it is possible to prevent fluctuations in the supply voltage from being impressed on the grid.

Resistance condenser filters are also provided in the space current supply circuit in addition to the usual inductance condenser filter. Such filter stages are adapted for use in the supply to the first stages, particularly when these stages are operated at lower voltages than the last stages. In such cases the resistance elements of the filter can be chosen so as to reduce the voltage to the desired value. Additional potentiometer filter stages of this type can also be provided for reducing and further purifying the grid biasing potential for the tubes of the first stage.

It has also been found that electrolytic rectifiers employing film forming plates are well suited for rectifying power supply especially as they may be provided with extra plates, which, because of the high capacity between the plates and the electrolyte, are very well adapted for use as shunt elements of the smoothing-out filter.

In one form, this invention comprises a two stage amplifier employing two tubes in a push-pull circuit in the last stage and a single low voltage filament tube in the first stage. Power is supplied to the amplifier from an alternating current source, the filaments being heated with alternating current and the current being rectified for the plate

voltage supply. The supply to the tubes of the last stage is filtered by means of an inductance condenser filter. Resistance and condenser elements are arranged in the supply circuit to further filter and reduce the voltage supplied to the tube of the first stage. The grid biasing potential for the last stage is obtained by connecting a resistance in the plate current circuit and connecting the grids 5 through a resistance condenser filter to the terminal of the resistance adjacent the negative terminal of the space current supply. An additional resistance condenser filter stage is included to reduce and purify the 10 potential supplied to the grid of the tube of the first stage.

This invention will be more clearly understood by reference to the following description in connection with the drawings in 20 which:

Fig. 1 shows a two stage transformer coupled amplifier embodying certain features of this invention.

Fig. 2, a three stage resistance coupled 25 amplifier embodying other features of the invention.

Fig. 3, a two stage amplifier employing 30 two tubes in push-pull circuit in the last stage and embodying still other features of this invention.

Fig. 4, a modification of the two stage amplifier circuit of Fig. 1, and

Fig. 5, a power supply circuit for electron tubes comprising an aluminum plate rectifier and a multi-stage smoothing out filter employing electrolytic condensers as shunt elements.

In Fig. 1 a two stage amplifier is shown 40 employing two three-electrode tubes 6 and 7 which are coupled together and to the input circuit 8 and output circuit 11 by means of the inter-stage transformer 10, input transformer 9 and output transformer 12. The tubes are energized from the alternating current source 13, power being supplied through 45 the transformer 14, the primary winding 15 of which is connected to the source. The cathodes are heated with alternating current supplied directly from the secondary winding 16, the connections from the cathodes to 50 the grid and plate circuits being made at the mid-point of the secondary winding much in the same manner as is disclosed in the White Patent No. 1,195,632 granted August 22, 1916, 55 so as to prevent undue disturbances in the output circuit 11 due to the alternating current supplied to the filaments. A rectifier 17 which may be, for example, a two electrode electron discharge rectifier as is shown, supplies 60 plate current to the two tubes. The output of the rectifier is smoothed out by means of a filter comprising a series inductance 18 and two shunt condensers 19 and 20. The path of the plate currents for the tubes 65 6 and 7, for example, may be traced from

the anodes of the two tubes, through the primary windings of transformers 10 and 12 respectively, inductance 18, secondary winding 21 of the transformer 14 to the cathode 22 of the rectifier 17 and through the space in the rectifier to the anode 23, through the resistance 24 to the ground connection which is connected to the mid-point of the secondary winding 16 of transformer 14 and thence to the cathodes of the two tubes 6 and 7. The grids of the two tubes 6 and 7 are connected through the secondary windings of the respective transformers 9 and 10 and resistance 25 to the terminal 26 of resistance 24 adjacent to the anode 23 of rectifier 17, which is the negative terminal of the plate current source. In this manner the grids are maintained at negative potentials with respect to the cathodes of tubes 6 and 7 by means of the RI drop in the resistance 24. 70 The large capacity condenser 27 serves to shunt the amplified currents around the resistance 24 so as to reduce the coupling between the input and output circuits of the tubes. If only a single condenser was used 75 in this manner it would have to be of very high capacity. However in addition to this element there are included, the resistance 25 and the condenser 28 which serve to further reduce the coupling between the input and 80 output circuits, to a value so small that it does not interfere with the operation of the 85 amplifier. By making the value of resistance 25 very high the capacities of the condenser can be reduced to very nominal values. Since 90 there is no direct current drawn by the grids of the tubes there is no direct current potential across the resistance 25 and the value 95 of this resistance is not limited thereby. It has been found that very good filter action 100 may be secured by setting the value of the resistance 25 at about the order of one megohm and using as large capacity condensers for 27 and 28 as is convenient.

This resistance condenser filter not only 105 serves to reduce the coupling between the output and input circuits of the tube but also prevents small fluctuations in the RI drop in the resistance 24, due to ripples in the output of the rectifier, from being impressed 110 on the grids of tubes 6 and 7 and being amplified thus producing objectionable disturbances in the output current of the amplifier.

Referring to Fig. 2 which shows a three 115 stage resistance coupled amplifier, the three electrode-electron discharge tubes 30, 31 and 32 which are coupled together and to the input and output circuits through the usual 120 circuit arrangements. The direct current battery 33 is shown for supplying the space current to all of the tubes, though this may be replaced by a rectifier arrangement similar to that shown in the other figures. In 125 addition to the resistance and condenser ele-

ments 34, 35, 37 and 38 which correspond respectively to the elements 24, 25, 27 and 28 of the circuit of Fig. 1, there are included the resistances 39 and 40 which constitute a 5 potentiometer to obtain grid potentials for the first two tubes and a capacity 41, which cooperates with the resistance 39 to still further reduce the disturbing potential which otherwise would be applied to these grids. In 10 this case there is a small potential drop in the resistance 35 because of the current drawn by the potentiometer but this drop may be made negligibly small, if the resistances 39 and 40 have values of the order of 15 one megohm and resistance 35 is about 50,000 ohms. The resistance 42 and the condenser 43 may be included to reduce interaction between the plate circuits of the first and last tubes.

20 Referring to Fig. 3, which shows a two stage amplifier employing two three-electrode tubes 51 and 52 connected in push-pull circuit in the last stage and a three-electrode tube 50 in the first stage, a transformer 53 connects the first tube 50 to the incoming circuit 8. The usual inter-stage and output transformers 54 and 55 couple the two tubes 51 and 52 to the first stage tube 50 and to the 25 output circuit 11 in the usual manner for push-pull operation.

25 Tubes in the amplifier are energized from an alternating current source, power being supplied to a transformer 56, the primary winding 57 of which is arranged to be connected to an alternating current source such as a house lighting circuit through a switch 58 and an attachment plug 59. The filaments of the tubes are heated with alternating current, being connected directly to the secondary winding 60 in a similar manner to that shown in the circuit of Fig. 1. The winding 60 is shielded by means of a grounded shield 61 in order to prevent longitudinal currents from affecting it and making the 30 amplifier noisy. Since the amount of noise in the plate circuit of a vacuum tube due to the filament being heated by alternating current is a function of the filament voltage and since any disturbance in the plate circuit of 35 the first stage tube 50 will be amplified by the tubes 50 and 51 before appearing in the output circuit 11, a low voltage filament tube is used in the first stage. This tube has a filament voltage which is preferably at least 40 as low as one volt. Filament current for tube 50 is, therefore, tapped off the secondary winding 60 at different points than those at which the filament current for the tubes 51 and 52 is tapped off.

45 A rectifier 62 supplies space currents to the tubes. The filament 63 of this tube is heated by alternating current supplied from the secondary winding 64. The alternating current which is applied to this tube to furnish a rectified current is provided by an

additional secondary winding 65. Filtering of this rectifier current is accomplished in the following manner. A condenser 67 is provided to complete the alternating current circuit which includes the high voltage secondary winding 65 and the rectifier tube 62. This condenser shunts the circuit into which the rectified current flows, thereby reducing the alternating potential applied to it. A 50 retardation coil 68 further prevents the alternating current from flowing in the path which the rectified current takes. Another condenser 69 reduces still further the alternating current potential applied to the plates of the tubes of the push-pull stage. The direct potential applied by the rectifier to the plates of tubes 51 and 52 is reduced to the somewhat lower potential applied to the tube 55 by means of a potentiometer consisting of two fixed resistances 70 and 71. A condenser 72 is connected to shunt the resistance 71 to afford a by-pass by means of which the alternating current in the plate circuit of the tube 50 may return to the filament after passing through the primary winding of the inter-stage transformer 54. This condenser performs the additional function of still further filtering any residual alternating current from the rectified current.

55 The grid biasing potential for the amplifier tubes is secured by passing the entire rectified current through a resistance 73. In order to eliminate any residual alternating current hum which may be present in the voltage drop across this resistance, and in order to prevent any coupling between the output and input circuits which may not be completely eliminated by the condenser 69, the resistance 74 and condenser 75 are employed, in much the same manner as the elements 25 and 28 of the circuit of Fig. 1, to filter the voltage applied to the grid. The potential drop across the resistance is reduced to a suitable value for applying to the grid of the tube 50 by means of a potentiometer consisting of resistances 76 and 77. As was the case in the circuit of Fig. 2, the resistance of this potentiometer should be high in order that the direct current flowing through the resistance 74 will be low and consequently cause 100 very little loss of voltage because of resistance drop. Another condenser 78 connected in shunt to the resistance 77 still further filters the voltage applied to the grid of the tube 50 thus reducing the residual hum which 105 may remain in spite of the use of the condenser 75, and it also provides a low impedance by-pass to the filament of tube 50 for charging currents to the grid of this tube. It should be noted in this connection that the condenser 67 is connected in such a manner as to shunt the alternating current flowing through rectifier tube 62 away from the resistance 73 thus rendering the voltage developed across this resistance more free from 110 115 120 125 130

fluctuations than if this condenser had been connected to ground. On the other hand, the condenser 69 is connected to ground thereby shunting away from the resistance 73 any voltage surges in the plate circuit of the push-pull stage which would occur if the stage were overloaded and which might otherwise result in blocking the amplifier and rendering it temporarily inoperative.

10 Amplification control is obtained by making the connection 79 to the secondary winding of the input transformer 53 variable. An equalizer network 80 is also shown connected in shunt to the primary of the input transformer 53 for making the resultant amplification and reproduction characteristic of the amplifier and loud speaker respectively more uniform. The effect of this network is controlled by means of the key 81. When 20 the key is actuated the network has the effect of making the amplification characteristic of the amplifier uniform over a very wide range of frequencies. When the key is in its normal position, that is, in the position 25 shown, the resistance connected in series with the equalizer is reduced thereby raising the amplification in the neighborhood of 140 cycles and, to a slight extent, in the neighborhood of 5000 cycles, while reducing 30 it considerably in the middle frequency range. An amplification characteristic of this type adapts the amplifier very well for use with certain horn type loud speakers which normally tend to distort the sound 35 considerably in the opposite manner.

The low filament voltage tube 50 may be, for instance, of the type commonly known as the 215-A and the tubes 51 and 52 may each be of the 216-A type, in which case it 40 has been found desirable to rectify a total current of 33 milliamperes of which 30 milliamperes supplies the plates of the tubes 51 and 52, a space current of 15 milliamperes being normal for each under these conditions.

45 One milliampere is the normal space current of the 215-A vacuum tube under the conditions imposed and the additional two milliamperes are lost in the potentiometer which is used for supplying the tube 50 with 50 plate voltage. In this circuit a satisfactory capacity value for the condensers 67 and 69 is 2 m. f., for the inductance 68, 15 henrys, resistances 70 and 71, 48,000 ohms and 30,000 ohms respectively, the condenser 72, 2 m. f., 55 a value of 565 ohms for the resistance 73 gives a grid biasing potential for the tubes 51 and 52 of 18 volts, in which case the filter resistance 74 and condenser 75 may be 48,000 ohms and $\frac{1}{2}$ m. f. The grid potential for 60 tube 50 should be reduced to $4\frac{1}{2}$ volts by means of the potentiometer comprising the resistances 76 and 77 for which the values $1\frac{1}{2}$ megohms and $\frac{1}{2}$ megohm respectively, are satisfactory while the condenser 78 may 65 have a capacity of $\frac{1}{2}$ m. f.

The circuit of Fig. 4 is the same as that of Fig. 1 except that an electrolytic rectifier 83 is used for rectifying the plate current supply. This rectifier consists of two aluminum plates 84 and 85 and a third electrode 70 75 87, which may be composed of lead, tin, carbon or other inert conductor, immersed in an electrolyte which may be for example a solution of ammonium borate. Such an arrangement will permit current to pass from the lead plate but never from the aluminum plates so that when the aluminum plates 84 and 85 are connected to the terminals of the secondary winding 86 rectified current may be drawn from the midpoint of the secondary winding 88 and the plate 87 which serve as the positive and negative terminals respectively and this current can be passed through the smoothing out filter in the manner shown.

85 Fig. 5 shows a power supply circuit for the electron tubes 90, 91, 92 and 93 which may be used in an amplifier circuit, for example. The leads to the grids and plates are shown dotted to indicate the omission 90 of the connections by which the tubes are associated in the circuit in which they are employed.

95 Power is supplied through the transformer 94 which has its primary winding 95 connected to the alternating current source 96. The filaments of the tubes are heated by means of alternating current being connected to the secondary winding 97 of the transformer 94. Connections from the cathodes 100 to the grids and plates are made at the midpoint of the secondary 97 in a similar manner to that in the circuit of Fig. 1.

An electrolytic rectifier 98 which operates 105 in a similar manner to the rectifier of Fig. 4 supplies plate current to the tubes. In this case the electrolyte is contained in a tin tank 99 which serves as the anode. The oxide coating which forms on the surface of the aluminum plates 101 and 102 and by virtue 110 of which the rectifier functions also forms the dielectric for a high capacity between the plates 103 and 104 and the electrolyte. Thus, by including extra plates in the bath, high capacity condensers for use in the 115 smoothing out filter may be obtained. In the circuit shown two plates 103 and 104 are used. These are connected at each side of the retardation coil 105, which is connected 120 in series with the lead from the midpoint of the secondary winding 100. The dotted capacities 106 and 107 represent the capacity between the plates 103 and 104 and the electrolyte, which capacities shunt the circuit into which the rectified current flows thus 125 reducing the alternating current potential applied to that circuit.

130 The point 108 is connected to the plate of the tube 93 for supplying the plate voltage. The rectifier output is then further filtered

5 by means of the inductance 109 and additional electrolytic condenser elements. These elements may be formed by using more plates in the same bath, though this method is found to have certain disadvantages.

10 Since the rectifying plates 101 and 102 normally receive rectified current impulses flowing to them from tank 99 by the way of the electrolyte contained within and surrounding them, the rectifier circuit being completed through plate 103 and capacity 106 to the electrolyte and back to the tank, and since in flowing through the electrolyte these currents cause potentials to be established in the directions of the paths taken by these currents, owing to the resistance of the electrolyte to such currents, and that these potentials cause potential gradients to be established in all of the electrolyte surrounding these plates, 15 it is apparent that any plate immersed in such an electrolyte will have impressed upon it from the electrolyte a potential which is equal to the average potential existing over that area of the electrolyte in which the plate is immersed. As long as this stray potential is small with respect to the potential impressed upon the plate from the circuit, as in the case of the first section of a filter, this stray potential causes little effect; but if the 20 stray potential becomes appreciable with respect to the potential impressed upon it from the circuit, as in the case of succeeding sections of the filter, the stray potential will have deleterious effects often to the extent of rendering these succeeding filter sections ineffectual. It is therefore desirable to mount the additional condenser plates in a separate tank. In this case additional filtration is provided by means of a plate 111 mounted in the tank 25 110. This electrolytic condenser and the retardation coil 109 serve to further filter the current supplied to the plate of the tube 92.

30 The plate current for the tubes 90 and 91 is filtered by means of the resistance condenser filter stages comprising the resistances 114 and 115 and the plates 112 and 113. The resistances 114 and 115 are so proportioned as to reduce the plate voltages to the desired values.

35 The grid biasing potentials are obtained by an arrangement similar to that of the circuit of Fig. 2. A resistance 134 which corresponds to the resistance 34 of the circuit of Fig. 2 being included in the rectified current circuit and the IR drop in this resistance being impressed on the grids of the tubes 92 and 93 after being filtered by the action of the condensers 137 and 138 and the resistance 135 in a manner similar to that of the circuit of Fig. 2. Similarly the potential for the grids 40 of the tubes 90 and 91 is reduced and further filtered by the use of the resistances 139 and 140 and the condenser 141 which corresponds to the elements 39, 40 and 41 of Fig. 2.

45 While this invention has been described in connection with specific circuits embodying its

features it should be understood that it is not limited to these specific circuits and particularly it should be understood that the term "amplifier" is meant to be generic to other circuits such as oscillators or detectors.

70 What is claimed is:

1. A multi-stage amplifier comprising a thermionic cathode electron tube in one stage and a thermionic cathode electron tube in a preceding stage, said second mentioned tube being adapted to operate at a lower anode-cathode potential than said first tube, a source of alternating current potential, a transformer, a primary connected to said source, and an associated secondary, said secondary having a tap at the mid-point, connections from said secondary to the cathodes of said tubes for supplying heating current of the proper potential thereto, a rectifier having its input terminals connected to said source, an inductance connected to the positive terminal of said rectifier, a condenser connected between the terminal of said inductance remote from said rectifier and the mid-point of said secondary, a connection from the above mentioned terminal of said inductance to the anode of said first mentioned tube, a resistance having one terminal connected to the above mentioned terminal of said inductance and the other terminal connected to the anode of said second mentioned tube, an impedance connected between the negative terminal of the rectifier and the mid-point of said secondary winding, a connection from the terminal of said impedance adjacent the negative terminal of said rectifier to the control electrode of said first mentioned tube, said connection including a high resistance element, a condenser connected between the terminal of said resistance element remote from said impedance and the mid-point of the secondary winding, a potentiometer connected in shunt to said condenser, a connection from a tap on said potentiometer to the control electrode of said second mentioned tube, and a condenser connected in shunt to the portion of said potentiometer between said tap and the mid-point of said secondary winding.

110 2. In a multi-stage amplifier comprising a plurality of electron tubes, a source of alternating current, an electrolytic rectifier comprising a film forming aluminum electrode and non-film forming electrode immersed in the electrolyte, a connection from the positive terminal of the rectifier to the anode of one of said tubes said connection including an impedance element, another film forming aluminum plate immersed in the electrolyte and connected to one terminal of said impedance element, a connection from the positive terminal of said rectifier to the anode of another one of said tubes, said connection including a second impedance element, and an electrolytic condenser comprising a film forming aluminum plate connected to the

above mentioned terminal of said second impedance element and immersed in an electrolyte contained in a separate container from that of the rectifier and a non-film forming plate connected to the negative terminal of the rectifier.

3. In a multi-stage vacuum tube amplifier circuit, adapted to be supplied from a source of rectified alternating current, common circuit means comprising series impedances and shunt capacities for obtaining successively higher positive potentials for the anodes of said vacuum tubes and to eliminate noise currents from said anode circuits arising in said source, and common circuit means comprising other series impedances and shunt capacities for obtaining successively higher negative potentials for the control electrodes of said vacuum tubes and to eliminate noise currents in said control electrode circuits.

4. A multi-stage vacuum tube amplifier in accordance with claim 3 in which said source of rectified current comprises electrolytic rectifier means rectifying an alternating current supply, said means containing electrodes forming certain of said shunt capacities.

5. A current and voltage supply network for a plurality of vacuum tubes in tandem comprising a series resistance having its terminals connected to a source of voltage, a common connection from the resistance to the cathodes of the tubes, tap points on the portions of said resistance included between said common cathode connection and the positive terminal of the resistance for supplying successively higher values of anode voltage to the successive tubes, other tap points on the portion of the resistance on the other side of the common cathode connection for supplying successively higher values of negative biasing voltage to the grids of the successive tubes, an individual condenser connected between the common cathode connection and each of said tap points and a filter means connected across the entire resistance, said condensers and filter means serving to suppress noise components arising from the supply source.

50 6. In a multi-stage amplifier having a plurality of electron tubes, each having a thermionic cathode, an anode, and a control electrode connected in a plurality of stages, a source of rectified alternating current, a resistance having a terminal connected to the negative terminal of said source and another terminal connected effectively to the cathodes, said resistance lying in the path of the rectified current, a second resistance in shunt to said first resistance and large compared to the first resistance, a connection from the control electrode of one of said stages to a point in said shunt resistance, a connection from the control electrode of a stage subsequent to the first mentioned stage

to a point in said shunt resistance intermediate the first mentioned point and the negative end of the resistance whereby the control electrode of the subsequent stage receives a larger negative bias than that of the other stage, and individual condensers connected between the said points of connection to said shunt resistance and the cathodes.

7. In a multi-stage amplifier having a plurality of electron tubes connected in a plurality of stages, one of said tubes being adapted to work at a lower anode-cathode potential than another of said tubes in a subsequent stage, a connection between the cathodes of said tubes, a rectifier for supplying space current to said tubes, a smoothing-out filter comprising an impedance in series and a plurality of condensers in shunt to the path of the rectified current at different points on said impedance for filtering the space current to said tubes, connections from the output of said filter to the anode of said last mentioned tube, and to said common cathode connection, a potentiometer connected across the output of said filter and having a tap connected to the anode of said first mentioned tube, the shunt capacity provided by said condensers together with the resistance of the portions of said potentiometer between the connections to said cathode connection and to said respective anodes serving to eliminate from the circuits of said anodes the noise currents arising in said rectifier, an impedance connected between said common cathode connection and the negative terminal of said rectifier and connections from different points of said impedance for supplying different negative grid potentials to said tubes, said impedance and shunt condensers providing a smoothing-out filter to eliminate from the circuits of said control electrodes the noise current arising in said rectifier.

In witness whereof, I hereunto subscribe my name this 14th day of November A. D. 1924.
